Application December 26, 1944, Serial No. 569,719

5 Claims. (Cl. 259—96)

1

This invention relates to apparatus suitable for use in thoroughly mixing, blending, emulsifying, homogenizing and/or dispersing mixtures of liquids with other liquids, gases and/or solids.

When mixing a liquid with another liquid of substantially the same viscosity and general character, or when mixing a liquid with a solid which is already in a sufficiently finely divided condition, ordinary mixing apparatus usually suffices. When, however, any of the materials to be mixed require emulsification, homogenization or attrition to insure the desired ultimate blending, ordinary mixing apparatus will not usually produce the desired ultimate result. The present invention aims, therefore, to provide improved apparatus which is useful to effect the desired dispersion of one liquid in another or of a gas or of a solid in a liquid, as, for example, by providing for attrition of any solid particles which are in the liquid or the breaking up of any globules suspended in the liquid or such other treatment as may be necessary to secure complete blending, emulsification or homogenization of the materials to be treated.

An important feature of the invention is the provision of means for effecting a hydraulic shearing of the materials treated, this means serving to produce the hydraulic shearing action both by direct impact of liquid streams against shearing edges and by mechanical movement of co-operating shearing edges through streams flowing thereacross.

Another important feature of the invention is the provision of substantially contiguous relatively movable perforated plates or screens, which are so relatively movable to each other as to bring the openings in each screen gradually into and out of register with openings in the other, in combination with means for driving liquid to be treated through said screen openings during such relative movement and when and so long as any parts thereof are in register. It will be seen that this feature of the invention provides for a manifold shearing action which facilitates the blending, emulsifying and homogenizing action of the apparatus.

Still another important feature of the invention is the connection of the means for effecting the relative movements of the perforated screens to the means for effecting the liquid flow in such manner that these actions are synchronized, whereby the apparatus can readily be operated at various speeds to adapt it for use with liquids of different viscosities and with various combinations of materials to be treated.

2

In apparatus for treating those mixtures to be blended, emulsified or homogenized in which breaking up of solids into a more finely divided condition is essential to secure the desired ultimate result it is important that the apparatus include also attrition means. The invention therefore further contemplates the combination with the aforementioned means for effecting a hydraulic shearing, of means for effecting an introduction of the solid particles between the surfaces over the edges of which the hydraulic shearing has taken place whereby the solid particles are carried between the surfaces of the movable and stationary plates and a grinding thereof is effected by the relative movement of said plates.

Other objects and important features of the invention to which attention has not hereinabove specifically been directed will appear hereinafter when the following description and claims are considered in connection with the accompanying drawings, in which—

Figure 1 is a section through combined mixing and homogenizing apparatus embodying the present invention;

Figure 2 shows a modification of the embodiment illustrated in Figure 1 in which two pairs of shearing screens are provided;

Figure 3 shows other means for effecting the relative movements of the shearing screens of apparatus embodying the present invention;

Figure 4 is a vertical section through another embodiment of the invention in which other means for effecting the relative movements of the shearing screens are provided;

Figure 5 is a vertical section through still another embodiment of the invention in which the shearing screens are arranged in horizontal planes;

Figure 6 is a transverse section through the perforated plates or screens of Figure 5 showing one construction and arrangement of the screens or plates adapted to produce the desired attrition of the materials to be treated, the parts being arranged for self cleaning;

Figure 7 is a section similar to Figure 6 showing a modification of the plate constructions for producing substantially the same results as are obtained by the construction shown in Figure 6;

Figure 8 is a view similar to Figure 6 showing still another modification of the plate constructions for securing substantially the same results as are obtained by the Figure 6 construction and arrangement;

Figure 9 is a composite view showing different

shapes and sizes of apertures suitable for use in the screen plates of Figures 5, 6, 7 and 8;

Figure 10 is a sectional view of another embodiment of the invention in which the shearing screens are incorporated in a mixing apparatus of another type, the screens being inserted in the discharge end of the apparatus shown in this figure.

Figure 11 is a view similar to Figure 10 but showing the screens located in the intake end of the apparatus.

In the embodiment of the invention shown in Figure 1, mixing apparatus of the inclined flow type, such as more fully disclosed in the pending application Serial No. 563,500, filed November 15, 1944, now Patent No. 2,450,802, dated October 5, 1948, has incorporated therein the means for effecting a hydraulic shearing of the materials being mixed which characterize the present invention, such means being preferably adapted to function also as an attrition mill. In this embodiment of the invention a liquid circulating rotor, comprising propeller blades 2 carried by a central hub 4 attached to a driving shaft 6, serves to effect the flow of the liquid or liquids through the mixing, blending, homogenizing or emulsifying apparatus. To insure the desired inclined flow of the propelled liquid the propeller blades 2 have their discharge edges 8 inclined to the axis of rotation of the shaft 6, the inclination shown in Figure 1 being at an angle of substantially 35° to the axis of rotation of the shaft, or 55° to the horizontal. The liquid circulating rotor is also provided with a flow directing shroud 10 carried upon the outer ends of the propeller blades 2, this flow director being shaped, as shown, to insure the desired inclined flow which, as also shown, is gradually converted into a substantially horizontal flow by reason of the impact of the liquid against the bottom 12 of the tank or other container in which the combined mixer and blender is located.

As in the mixer more fully shown and described in the Patent No. 2,450,802, hereinabove referred to, stator blades 14 are so located beneath the propeller blades 2 of the rotor that their liquid-receiving edges 16 are parallel to the surface generated by the edges 8 of the blades 2 and lie substantially within the vertically projected periphery of the path of travel of the edges 8. Preferably the shroud 10 extends over the entire width of the stators 14 so as to insure direction of the flow through the stator part of the mixer.

Adjacent to the discharge side of the stator part of the mixer a cylindrical plate or screen 18 is located which is provided with numerous perforations 20 so that the stream of liquid directed against the screen is broken up into small jets. The walls of the holes or perforations 20 may be normal to the faces of the screen 18 or they may be inclined to the screen to secure any desired shearing and jet effect. As shown in Figure 1, however, the openings 20 are so formed in the screen 18 that the walls of the openings are normal to the two faces of the screen for the major part of the length of opening. The screen 18 may be supported in fixed relation to the liquid circulating rotor in any suitable manner as, for example, connecting it directly to the outer edges of the stators 14 as shown at 22.

To increase the hydraulic shearing effect in the embodiment of the invention illustrated in Figure 1, means are provided for producing a mechanically shearing relative movement of registering jet openings in two screens rela-

tively movable to each other. In the embodiment of the invention shown in Figure 1, a second cylindrical screen 26, in substantially contiguous or rubbing relation to the screen 18, surrounds this screen and is so connected to an upturned flange 28 on the shroud 10 of the liquid circulating rotor by rivets 30 or other connecting means that it rotates with the liquid circulating rotor. The openings 32 in the screen 26 are so located that they may be brought into register with correspondingly located openings 20 in the screen 18 as the screens move relatively to each other.

From the foregoing description it will be seen that the materials to be mixed, including the liquid or liquids constituting a part of the mixture, are drawn into the intake of the circulating rotor by the action of the propeller blades 2 and that as they leave the discharge edges 8 of the propeller blades 2 they strike the receiving edges 16 of the stator blades 14 and are directed by said stator blades 14 outwardly against the screen 18. As the force of the stream produced by the circulating rotor drives the liquid through the openings 20 in the screen 18 the liquid will pass through said openings 20 and into registering openings 32 of the screen 26 when these openings 32 are either wholly or partly in register with the openings 20. The rotation of the screen 26 with the liquid circulating rotor will first bring the openings 32 into partial register with one set of the openings 20, then into complete register, then again into partial register and finally into non-registering relation thereto but into register with the succeeding set of openings, the result being that each of the jets through the registering openings 20 and 32 are successively sheared and their cross-sectional dimensions constantly varied. This obviously increased the homogenizing and emulsifying action and at the same time, by reason of the projection of these jets into the slowly moving mass of liquid outside the screens, a thorough commingling and blending of all of the different materials in the mixture is brought about.

It is, of course, possible to so locate the successive sets of openings 20 in the screen 18 and the corresponding sets of openings 32 in the screen 26 that there will be no complete shut off of the flow of the liquid through the two screens at any time. This, however, is more or less immaterial if the speed of the relative movement of the two screens is sufficiently great so that the registering of the openings is substantially continuous.

In Figure 2 of the drawings is illustrated a slight modification of the embodiment of the invention shown in Figure 1, in which two stationary screens 34 and 36 are arranged in concentrically spaced relation to each other and are supported upon a plate 38 attached to the bottom of the tank in any suitable manner, this plate 38 also carrying the stator blades 14. Two cooperating rotary screens 40 and 42 are supported by studs 44 and 46, respectively, having reduced threaded ends extending through a horizontal flange 48 on the shroud 10 of the liquid circulating rotor and secured thereto by nuts 50 and 52. It will be seen that the jets, first driven through the rotary screen 40 and the stationary screen 34, then strike the rotary screen 42 and pass through that and through the registering openings of the stationary screen 36.

In Figure 3 is shown a modification of the invention in which stator blades 14 are done away

with and their place is taken by blades 54 carried upon a floating rotary frame comprising arms 56 attached to a hub 58 mounted to turn freely on the shaft 6 of the liquid circulating rotor. The arms 56 carry a section 60 of the flow directing shroud which is relatively movable with respect to the part of the shroud 10 carried by the liquid circulating rotor. The blades 54 are carried by the section 60 of the shroud which is attached to the arms 56. The stationary screens 34 and 36, as in the form of the invention shown in Figure 2, are carried by a plate 38 secured to the bottom of the tank and the rotary screens 40 and 42 are carried upon a horizontal flange 48 forming, in this instance, a part of the section 60 of the flow directing shroud.

From the foregoing description it will be seen that the movement of the screens 40 and 42 relative to the screens 34 and 36 is effected by the impact of the liquid discharged from the propeller blades 2 against the blades 54 carried by the shroud section 60. The blades 54 thus not only perform the function of the stator blades 14 in the form of the invention shown in Figure 1, but they also act to effect the rotation of the arm 56 and the parts connected thereto about the shaft 6 and thus produce the movement of the screens 40 and 42 relative to the stationary screens 34 and 36.

In the embodiment of the invention shown in Figure 4 the rotary screens are again brought outside the stationary screens, as in Figure 1, but the rotary screens 62 and 64 are mounted upon a rotary disk 66 having a central hub 68 secured to the upper end of a shaft 70 extending through the bottom 12 of the tank and the stationary screens 72 and 74 are suspended from a horizontal plate 76 by studs 78 and 80, similar to those employed in the construction shown in Figures 2 and 3, the plate 76 being itself supported on vertical studs 82 secured to the bottom 12 of the tank in which the mixing and blending apparatus is located.

In each of the forms of the invention so far described the screens or perforated plates, through which the mixture carrying liquid is forced in jets through registering openings, may also serve to effect attrition or grinding of any solid constituents of the mixture or the breaking up of fat globules and to this end they may be constructed as more fully shown in Figures 6, 7 and 8, to which more specific reference will be made hereinafter. When, however, attrition is an important function of the apparatus a construction such as shown in Figure 5 is preferably employed.

In the embodiment of the invention shown in Figure 5 the movable perforated plates or screens are shown as arranged in horizontal planes and the stationary perforated plates or screens are likewise, of course, arranged in horizontal planes. Each movable perforated plate or screen may be arranged to cooperate with a single stationary plate or screen associated therewith, as in Figures 1 to 4 inclusive, but where, as above suggested, attrition is an important function of the apparatus, it is preferred to arrange each movable plate so that it cooperates with two stationary plates, or vice versa. As shown in Figure 5, four movable perforated plates or screens are shown as arranged to cooperate with four pairs of horizontal plates or screens so arranged with respect to the movable plates or screens that each movable plate rotates between the two stationary plates of its associated pair.

As further shown in Figure 5, the liquid circulating rotor has the overhanging part 84 of its shroud 10 provided with vertically bored bosses 86 in which are mounted studs 88 having reduced threaded ends extending through the bores in the bosses 86 and secured therein by nuts 90. The four perforated annular or segmental plates or screens 92, 94, 96 and 98 are mounted on the studs 88 in any suitable manner to secure them in the desired vertically spaced relations to each other thereon and also in the desired relations to the stationary perforated blades or screens. As herein shown each screen is provided with upper and lower collars 100 and 102 fitting on the stud 88 and adapted to be pinned, welded or otherwise secured in position thereon to hold the associated movable perforated plate or screen in its proper position on said stud 88.

As above suggested, each movable perforated plate or screen is arranged to cooperate with two stationary plates or screens or vice versa, the movable plate in each case being located between the two stationary plates. In the embodiment of the invention shown in Figure 5, the movable perforated plate 92 moves between two contiguous stationary plates 104 and 106; movable plate 94 moves between two contiguous stationary plates 108 and 110; movable plate 96 moves between two contiguous stationary plates 112 and 114 and movable plate 98 moves between two contiguous stationary plates 116 and 118. As also shown, all of these stationary plates are mounted on stationary studs 120, each having a head at one end and a nut at the other end to clamp the plates and their separating washers and collars and the flow directors in position on the studs. The studs 120 may be held in stationary position in any suitable manner such, for example, as attaching them to supports in turn secured to the bottom of the container 122 in which the apparatus is located.

Associated with each group of plates, that is, with each movable plate and its associated pair of stationary plates, is a flow director. The flow director 124 for the uppermost group of perforated plates or screens is shown as mounted on the studs 120 and having its inner edge adjacent to the outer edge of the overhanging part 84 of the shroud 10 of the liquid circulating rotor. The flow director 124 thus serves to guide that part of the stream of liquid discharged from the rotor, which passes over the upper movable plate or screen 92, through the perforations in the screen, the space provided between the flow director 124 and the uppermost stationary screen 104 being tapered as shown to insure substantially equal distribution of the liquid among and substantially uniform velocity of flow thereof through the perforations in the uppermost group of perforated plates or screens.

The flow directors 126, 128 and 130 for the respective groups of perforated plates or screens below the uppermost group are shaped as shown with a bent-up portion near their inner ends which engages the inner margin of the associated lower stationary plate of the respective groups, in order not only to insure the direction of the flow of a part of the rotor driven stream toward this group but to assist somewhat in supporting the inner edge of the lower plate of the group and maintain it in rubbing contact with the movable plate. It will be seen that the flow director 126 maintains the lower plate 106

in engagement with the under face of the movable plate 92 of the uppermost group.

These various elements which are mounted on the studs 120 are suitably spaced thereon as follows:

Spacing collars 132, 134 and 136 are located respectively between the lowermost plate 106 of the uppermost group and the flow director 126, between the lowermost plate 110 of the next group and the flow director 128, and between the lowermost plate 114 of the third group from the top and the flow director 130. Spacing sleeves 138, 140, 142 and 144 extend between the respective flow directors 124, 126, 128 and 130 and the bottom plates of the respective groups, namely, 106, 110, 114 and 118. The upper plates 104, 108, 112 and 116 are freely slideable on the sleeves 138, 140, 142 and 144 so that the uppermost stationary plate of each group is permitted to bear with its own weight against the upper face of the associated movable plate.

To insure entrance of the particles to be broken up between the stationary and the movable plates, the openings 20 in the stationary plates or the openings 32 in the movable plates or both may have their marginal edges cut back to provide recesses between the plates and adjacent to the openings, into which recesses the particles can enter to cause their introduction between the plates. The openings 20 and 32 may be either circular, elliptical, square or of any other desired shape, such as shown in Figure 9, but for ease of production they are preferably circular. When circular openings are provided it is comparatively easy to ream them to provide beveled recesses between the plates adjacent to the openings. Even when the openings are of other shapes, if the plate be made by die stamping or die casting the beveling of the edges of the openings to provide the cut-back margins is a comparatively simple operation.

As shown in Figures 6, 7 and 8, the provision of the particle-receiving recesses adjacent to the plate or screen openings is accomplished in three different ways. In Figure 6 the lower margins of the openings 20 in the upper stationary plate of each group are shown as cut back at 146 and the upper margins of the openings 20 in the lower stationary plate of each group are likewise shown as cut back at 148. The margins of the openings 32 in the rotary plate of each group are shown as flush with the surfaces of the plate. In Figure 7 the margins of the openings 20 in the stationary plates are kept flush with the operative surfaces of the plates while both the upper and lower margins of the openings 32 in the movable plate of each group are shown as cut back at 150 and 152, respectively. In Figure 8 substantially the same result is produced by leaving the margins of the openings 20 in the lower plate flush with its operative surface, cutting back the lower margins of the openings 32 in the movable plate on one side only of the openings, that is, the trailing side as shown at 154, and cutting back one side only of the margins of the opening 20 in the upper stationary plate, likewise on the side last engaged, or trailing side, as shown at 156.

It will be apparent that other arrangements of the recesses on the respective plates may be made to facilitate the introduction of solid particles to be ground between the faces of the stationary and movable plates.

In Figures 1 to 5 inclusive of the drawings the

present invention has been shown as incorporated in a mixer of the type disclosed in the Patent No. 2,450,802. In Figures 10 and 11 there has been shown the invention as incorporated in a somewhat different type of mixer, that is, a mixer known commercially as the Stevens type of mixer converging flow-directing stator blades 158, projecting inwardly from the wall of a hopper-like flow-directing tube 160, direct the liquid to the blades 162 of a rotary propeller having a hub 164 mounted on a shaft 166.

To produce the desired homogenizing or emulsifying action in the embodiment of the invention shown in Figure 10, a stationary perforated plate or screen 168 is fixed in the discharge end of the flow directing tube 160 and a contiguous cooperating screen 170 is mounted on the shaft 166 to cause its perforations 32 to move into and out of register with the perforations 20 of the stationary screen 168.

In Figure 11 the stationary screen 168, instead of being located at the discharge end of the Stevens type mixer, is located at the intake end, as shown at 170, and the rotary screen 172 is mounted on the outside of the stationary screen 170 instead of being upon the inside, as shown in Figure 10.

From the foregoing description it will be seen that the invention provides improved means for insuring not only a thorough mixing of a liquid with another liquid or of a liquid with a solid or a gas, but also such a dispersion of the materials to be mixed throughout the mixture as to insure the desired complete blending of the materials. It will further be seen that the hydraulic shearing effect produced by the relative movement of the contiguous perforated plates or screens insures homogenization and emulsification of those mixtures requiring such treatment and that where attrition of solid particles is essential to the complete ultimate blending of the materials, such attrition is insured both by the shearing action and by the grinding of the materials between the contiguous plates.

In designing the apparatus to insure adequate attrition, it will be understood that the contiguous faces of the stationary and movable plates may be provided with abrading surfaces and also, if desired, with suitable grooves in order further to facilitate the introduction of the materials to be ground between the abrading surfaces, where considerable attrition is important. The grinding plates may, if desired, be made of powdered metal with diamond dust, powdered Stellite, silicon, carbide or other abrasives mixed with the powder before compacting and sintering and the grinding surfaces of the plates may be treated in any suitable way, as by etching to expose the abrasive materials. The plates might also be made of steel faced with a softer material, such as copper, having the abrasive pressed into the face thereof, or the plates could be faced with a mixture of powdered metal and abrasive, compacted and sintered as above described. In fact, any of the commercial methods of embedding abrasive materials in the surfaces of surface grinders might be employed to increase the attritive effect of the perforated plates or screens of the present invention.

What is claimed as new is:

1. In homogenizing apparatus or the like, the combination with substantially contiguous screens so relatively movable as to bring the openings in each gradually into and out of register with openings in the other, of means for

effecting such relative movement and means operating while such relative movement is taking place to drive liquid to be treated through said screen openings when and so long as any parts thereof are in register, including direction changing means between the driving means and the screens for positively directing the driven liquid toward the screen openings in directions substantially normal to the screen surfaces, said relatively movable substantially contiguous screens having tapered passages leading away from at least some of the screen openings in the direction to effect by the relative screen movement the gradual introduction of the liquid or liquids and any other materials suspended therein between the substantially contiguous screen surfaces to insure attrition of the materials thus brought into rubbing relation to said surfaces.

2. In homogenizing apparatus or the like, the combination with substantially contiguous screens so relatively movable as to bring the openings in each gradually into and out of register with openings in the other, of means for effecting such relative movement and means operating while such relative movement is taking place to drive liquid to be treated through said screen openings when and so long as any parts thereof are in register, including direction changing means between the driving means and the screens for positively directing the driven liquid toward the screen openings in direction substantially normal to the screen surfaces, the substantially contiguous screen surfaces being faced with abrasive material and provision being made for gradually introducing liquid or liquids and any materials suspended therein between said substantially contiguous screen surfaces.

3. In homogenizing apparatus or the like, the combination with substantially contiguous screens so relatively movable as to bring the openings in each gradually into and out of register with openings in the other, of means for effecting such relative movement and means operating while such relative movement is taking place to drive liquid to be treated through said screen openings when and so long as any parts thereof are in register, including direction changing means between the driving means and the screens for positively directing the driven liquid toward the screen openings in directions substantially normal to the screen surfaces, said substantially contiguous screens being arranged in a plurality of segregated banks of three screens each in the path of flow of the liquid, each of said banks comprising inner and outer screens and an intermediate screen substantially contiguous to each of said inner and outer screens and relatively movable with respect to both and each having an intake and a discharge independent of the others.

4. In homogenizing apparatus or the like, the combination with substantially contiguous

screens so relatively movable as to bring the openings in each gradually into and out of register with openings in the other, of means for effecting such relative movement and means operating while such relative movement is taking place to drive liquid to be treated through said screen openings when and so long as any parts thereof are in register, including direction changing means between the driving means and the screens for positively directing the driven liquid toward the screen openings in directions substantially normal to the screen surfaces, the liquid driving means comprising a rotor having propeller blades and the relatively movable substantially contiguous screens lying in a plane substantially perpendicular to the rotor axis.

5. In homogenizing apparatus or the like the combination with substantially contiguous screens so relatively movable as to bring the openings in each gradually into and out of register with openings in the other, of means for effecting such relative movement and means operating while such relative movement is taking place to drive liquid to be treated through said screen openings when and so long as any parts thereof are in register, including direction changing means between the driving means and the screens for positively directing the driven liquid toward the screen openings in directions substantially normal to the screen surfaces, the substantially contiguous screens having portions of the contiguous face of at least one screen so cut away adjacent to the screen openings therein as to provide tapered passages leading away from said openings in the direction to effect by the relative screen movement the gradual introduction of the materials to be mixed between the contiguous faces to effect attrition thereof.

ETHEL H. JOHNSON,
40 Executrix of the Estate of John Johnson,
Deceased.
